UNITED STATES PATENT OFFICE

136,652

DESIGN FOR A LAWN CHAIR

Harvey A. Chapman, Minneapolis, Minn.

Application April 22, 1943, Serial No. 110,019

Term of patent 7 years

To all whom it may concern:

Be it known that I, Harvey A. Chapman, a citizen of the United States, residing at Minneapolis, in the county of Hennepin and State of Minnesota, have invented a new, original, and ornamental Design for a Lawn Chair, of which the following is a specification, reference being had to the accompanying drawing, forming part thereof.

Fig. 1 is a perspective view of the lawn chair, viewing the same from the side and showing my new design.

Fig. 2 is a perspective view of the lawn chair, viewing the same from the rear.

I claim:

The ornamental design for a lawn chair, as shown.

HARVEY A. CHAPMAN.
